UNITED STATES PATENT OFFICE.

JOHN H. BARR, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,215,762.

Specification of Letters Patent. Patented Feb. 13, 1917.

Application filed January 27, 1916. Serial No. 74,577.

To all whom it may concern:

Be it known that I, JOHN H. BARR, a citizen of the United States, and resident of the borough of Manhattan, city of New York, in the county of New York and State of New York, have invented certain new and useful Improvements in Type-Writing Machines, of which the following is a specification.

10 My invention relates to typewriting machines and especially to such typewriting machines as include case shift mechanism.

One of the objects of my invention is to provide improved case shift mechanism. I 15 have provided a platen shifting means for a front strike typewriter, said means being effective for its purpose and of very simple and light construction.

Another object of my invention is to provide a typewriting machine with an unusually large number of printing characters, but without unusual complexity in the mechanism and without making the machine of unusual size or the type bars of increased 25 length, and to use said machine for writing two widely different languages, such for example, as Russian and German. The machine shown in the accompanying drawings is capable of printing one hundred and fifteen 30 different characters, and the characters shown in the drawings are suitable, when used in the manner hereinafter described, for the two languages mentioned although other languages can be written with the same 35 characters as, for example, the English language.

To the above and other ends which will hereinafter appear, my invention consists in certain features of construction and combinations and arrangements of parts, all of 40 which will be fully set forth herein and particularly pointed out in the claims.

One embodiment of my invention is illustrated in the accompanying drawings in 45 which—

Figure 1 is a fore and aft vertical sectional view of the machine with some parts omitted and others broken.

Fig. 2 is a vertical sectional view of the 50 left-hand end of the carriage framework, and some of the associated stationary parts, the section being taken at the left of the platen and looking toward the left.

Fig. 3 is a view similar to parts of Fig. 1 55 but with the platen shown locked in shifted

position and with a type bar in printing position.

Fig. 4 is an isometric view of the upper part of the shift frame and its guide.

Fig. 5 is an isometric view on a smaller 60 scale than the other figures and showing the parts of the case shift mechanism located in the base of the machine.

Fig. 6 is a diagrammatic plan view of the 65 type bar system (developed) and the keyboard.

My invention is capable of embodiment in machines of various designs, but it is here shown in a machine having many of the characteristics of the Smith Premier 70 No. 10 typewriter, the construction of which machine is so well known in the art as not to require detailed description. Moreover, my machine as actually constructed can include many details of the Smith Premier 75 No. 10 machine which I have not thought it necessary to illustrate in the drawings.

The main frame of my machine, except for some obvious changes in the proportions, can be substantially like that of the Smith 80 Premier No. 10, and it is so shown in the drawings. Said frame includes side plates 1 having cast integral therewith posts 2, which support a top plate 3. Standards 4 rising from said top plate support a stationary rail 5, along which, by means of anti-friction balls 6, a carriage truck 7 is adapted to travel. The balls 6 are shown controlled by a spacer 8.

The right and left side plates 1 are connected together by the top plate 3, a keyboard plate 10, a front bar or plate 11, and by a rear connecting member not shown in the drawings but which is secured to the side plates by screws 12, Fig. 1; and said side plates may be connected by other devices also. The printing keys 13 are on stems 14, which project through the keyboard plate 10 and operate bell-crank 15, which are connected by links 16 with sub-levers 17, which by links 18 are connected with shorter type bars 20 and longer type bars 21, which type bars are, respectively, pivoted by ball bearings on segments 22 and 23. The type bars 20, 21 carry type blocks 24, some of which have two types each, and some one type each as shown in detail in Fig. 6. The sub-levers 17 are pivoted on a wire 25 mounted in a segment 26, and said sub-levers are controlled by returning 100 105 110

springs 27, and each of said sub-levers is adapted to operate a universal bar 28. The type bars normally rest against a pad 30.

With few exceptions, some of which have 5 been or will be noted, and others of which are obvious, the parts thus far described are substantially like, and in many instances identical with, the corresponding parts of the Smith Premier No. 10 machine.

10 I have modified the carriage truck 7 in order to adapt it for a platen-shift machine. Said truck comprises rails 31, which coöperate with the balls 6 in the same manner as in the Smith Premier No. 10 machine, and 15 said rails are secured by screws 32 to end pieces or brackets 33 in the same way as in the said machine, but the form of these brackets has been modified. Each of them has projecting from its forward end an upper 20 and a lower lug or bracket 34, and through said brackets are screwed upper and lower stop screws 35 having check nuts 36. Said stop screws are adapted to arrest the axle 37, or a sleeve or hub 38 thereon, of 25 the platen 40 when said platen is shifted up and down as hereinafter described.

The platen frame comprises a right-hand end piece 41, Fig. 1, a left-hand end piece 42, Fig. 2, and certain connecting devices. 30 These connecting devices include a rod 43 above the platen and grooved for coöperation with the usual paper fingers, not shown, and a lower rod 44; and they also include at the lower rear part of the platen frame 35 a channel bar or grooved rail 45, which is secured to the end pieces 41 and 42 in any suitable manner, as by screws. The platen-axle is journaled near its ends in the end pieces 41 and 42.

40 The platen frame is guided in its shifting movements by an upper pair of links 46 and a lower pair of links 47, said links being pivoted to the end pieces 41 and 42 by means of pivot screws 48. The links 46 consist of 45 arms rigidly mounted on a rock shaft 50, Figs 2 and 7, which rock shaft is suitably pivoted at its ends on pivot screws 51, Fig. 1, in the end pieces 33 of the carriage truck. The rock shaft 50 causes the two arms 46 to 50 swing up and down together as will be understood. The links 47 are here shown as separate links, each pivoted to one of the brackets 33 on a pivot screw 52, Fig. 2. Any suitable counterbalancing spring can be provided 55 for the platen and platen frame, such as the spring 49, shown in Fig. 3 coiled about the rock shaft 50 and connected at one end to said shaft.

The line spacing mechanism includes a line 60 space ratchet wheel 53 which is engaged by a dog, said dog mounted in a barrel 54, which barrel is mounted on the end of a line spacing rock shaft 55 which shaft is journaled in the right-hand end piece 41 of the platen frame. Said shaft projects toward the front

of the machine where it can be bent into any suitable form to constitute a handle. The mechanism can be adjusted to regulate the extent of line spacing by means of a handle 56. I have not shown any of said mechanism in detail because in the machine illustrated it is identical with the corresponding mechanism in the Smith Premier No. 10 typewriter, except that in the present machine the hand-operated parts of the line spacing mechanism are mounted in the end piece 41 of the platen frame instead of in the end piece of the carriage truck as in the Smith Premier machine referred to, this change having been made in order to enable 75 line spacing to be effected when the platen is in upper case position.

The drawings also show a rock shaft 57, Fig. 2, Pivoted to the platen frame in part by a screw 58, Fig. 1. This is the paper feed release shaft which in the present machine is similar to that of the Smith Premier No. 10, except that I have mounted it in the platen frame instead of in the truck in order to allow of the shifting of said platen 90 frame.

The case shift mechanism includes a roller or wheel 60, preferably situated at or near the middle of the machine, as viewed from the front. Said wheel runs in the 95 groove of the channel bar 45, as shown, and is of a diameter approximately equal to the width of said groove, which groove faces the rear of the machine. The wheel 60 is journaled on a pin 61, Fig. 4, projecting toward the front of the machine from a bracket 62 constituting part of a shift frame, which frame also comprises a vertical post 63 to which, as shown in the present instance, the bracket 62 is secured by screws 64. The 100 post 63 extends into the base of the machine where it is pivoted to a lever arm 65 by means of a pivot screw 66, said lever arm, as here shown, having its rear end in a vertical slot in the lower end of the post. The arm 65 is rigidly mounted on and at about the middle of a square rock shaft 67, which rock shaft extends transversely of the machine, being pivoted at its ends by pivot screws 68, Fig. 5, to the side plates 1 of the machine. One or more case shift keys 70 can be provided, two being shown in the present instance, mounted on the forward ends of arms 71, which at their rear ends are mounted 110 on and rigidly secured to the shaft 67 near the ends of said shaft. The arms 71 are here shown as stiffened by braces 72 each extending from the forward end of the arm 65 diagonally toward the front of the machine and secured at its forward end to one of the arms 71. It will be perceived that the whole frame including the arms 65, 71 and 72, constitutes in effect a lever of the first order, and the construction is such that when one of the keys 70 is depressed this lever is 115 120 125 130 135 140 145 150 155 160 165 170 175 180

rocked and the arm 65 moves the post 63 upward, the wheel 60 lifting the platen frame to upper case position, as shown in Fig. 3. The details of this shift key lever frame can, of course, be varied. As here shown the keys 70 are provided with separate systems secured by screws 73 to the forward ends of the lever arms 71, and said lever arms are themselves curved and shaped in such a way as to bring the keys 70 in line with the space key 74 of the typewriter. Each of the lever arms 65 and 71 is made of sheet metal and formed with a square perforation to fit the shaft 67, and at its end each of said lever arms is formed with a flap or ear 75 bent off perpendicularly to the rest of the lever arm in such a way as to lie flat against one of the flat sides of the rock shaft, to which it is secured by spot welding. The braces 72 are 20 here shown as bent in such a way that the forward end of each of them lies flat against the side of one of the lever arms 71 to which it is fastened by spot welding; and the rear end of each of said braces is similarly related and secured to the arm 65. When this 25 frame is completed, therefore, it constitutes in effect one integral piece, which is light and strong and inexpensive to manufacture. It will, of course, be understood that the 30 shift keys can be disposed in various ways, the particular arrangement shown being however a good one.

It will be perceived that the lever arm 65 is rigidly secured to the shaft 67, which 35 shaft is a long shaft pivoted at its ends and therefore held against any other movement than that of rocking about its own axis. The lower end of the post 63 is therefore 40 guided by the arm 65 with as much precision as is necessary for its purpose.

In order to guide the upper end of said post various means can be provided but I prefer the one shown in the drawings. Said means comprises a guide link or frame 76 45 extending in a front and back direction and having rigid therewith a rear cross piece or rock shaft 77 and a forward cross piece 78. The parts 76, 77 and 78 when seen from the top of the machine have the 50 shape of the letter H and all of said parts can be integral or be rigidly secured together as preferred. The forward cross piece 78 is pivoted at its ends on pivot screws 80 which pass through ears 81 bent upward 55 from the right and left-hand sides respectively of a bracket 82 constituting the upper end of, or rigidly mounted on the upper end of, the post 63. In the present instance this bracket is made of sheet metal having 60 right and left-hand arms, the ends of which are bent up to constitute the ears 81 and having also a rearwardly directed arm with ears bent downward and secured to the upper end of the post 63 by means of rivets 65 83. The cross piece 77 is pivoted on pivot

screws 84 passing through ears bent downward from the ends of a stationary sheet metal bracket 85, which bracket is suitably rigidly secured at 86 to the under side of the top plate. 70

The cross pieces 77 and 78 are of such length as effectually to prevent any objectionable sidewise motion of the post 63. It will be seen that the guide frame has a wide pivotal bearing on the stationary 75 framework which allows the forward end of the link 76 to move freely up and down about said bearing but which effectually prevents sidewise motion of said link; and the cross piece 78 is also of such length as 80 effectually to prevent wobbling of the upper part of the post 63 or turning of said post about a vertical axis.

I have provided a simple and convenient shift lock which includes a bell-crank 87, 85 which, as shown in the present instance, is located at the left of the front part of the keyboard and is pivoted to the left-hand side plate 1 on a pivot screw 88. This bell-crank has a downwardly extending arm and a forwardly extending arm, and a shift lock key 90 has its stem 91 pivoted at 92 to said forwardly extending arm. The lower arm of the bell-crank has its lower edge 93, Fig. 3, nearly concentric with the pivotal 95 axis of the lever; and in front of the part 93 the lever arm is formed with a stop lug or ear 94. Said lever arm is normally drawn toward the front of the machine to elevate the key 90 by means of a light spring 95 100 secured at 96 to a stationary part. The locking lever 87 is adapted to coöperate with a pin 97 projecting from one side of the left-hand shift key lever arm 71. I prefer to make this pin adjustable up and down so 105 as to regulate the action of the lock in a manner that will be understood and to this end said pin consists of a shouldered bolt or screw, the enlarged left-hand end of which projects out into position for coöperation with the lever 87 and the reduced part of which passes through a vertical slot 98 formed in the lever arm 71. The inner end of said bolt or screw is threaded and a nut 100 thereon can be loosened for the purpose 110 of adjusting the pin or screw up or down in the slot and when the right adjustment has been obtained the pin is secured in adjusted position by tightening the nut 100. The shift lock is normally in unlocking 115 position, but it can be moved to locking position by depressing the key 90, and it will then be held in locking position by friction on the pin 97. The lock can be released by striking a shift key 70, thus relieving said 120 friction and allowing the lock to be restored by its spring 95.

Any suitable ribbon vibrating mechanism can be mounted so as to shift up and down with the shift frame or post 63. In the 125

drawings the bracket 82 at the top of said post is shown with a forwardly and upwardly directed arm 101, the upper end of which is formed into vibrator guides 102,

5 Fig. 4. I have shown a vibrator 103 guided at its upper end in the guide 102 and having an ink ribbon 104 therein. Said vibrator at its lower part is pivoted on a lever 105, which lever has a long fulcrum or rock

10 10 shaft pivoted at 106 in the ears 81 above the cross piece 78 and said lever is shown connected at its rear end with an operating link 107. The vibrator connections shown in the drawings constitute parts of a ribbon vibrating mechanism invented by Arthur J. Briggs and shown in a pending application of his filed December 24, 1913, Serial No. 68,477. The wide bearing guide frame, 76, 77, 78, causes the vibrator guides

15 20 102 to be held and shifted with a sufficient degree of rigidity and precision.

The wheel 60 can, of course, be journaled in any suitable way but in the present instance the pin 61 is a smooth cylindrical pin 25 and the wheel has a hole through its center of a diameter suitable for turning on said pin. When the parts are mounted in the machine the wheel is prevented from slipping off the pin by the channel bar 45.

30 The keyboard and type bar systems are shown in part in side view in Fig. 1, and the arrangement thereof can be understood from Fig. 6. The type bar segment 22 stands within or above the segment 23 and 35 a little farther toward the rear of the machine than the segment 23, and the free ends of the shorter type bars 20 are, therefore, at some little distance back of the free ends of the longer type bars 21. The long and 40 short type bars alternate throughout the system so that each long bar, except the extreme right-hand end one, lies between two short ones; and each short bar, except the extreme left-hand end one, lies between two 45 long bars. As the free ends of the long type bars are all entirely free of the short type bars, I have provided all of said long type bars with double type blocks 24, that is to say, with type blocks each adapted to print 50 two characters. In the case of those shorter type bars, which are near the ends of the system, the necessary flare to the type blocks makes it inconvenient in some instances, and perhaps impracticable in others, to provide 55 them with the long type blocks necessary to print two characters; but the extreme left-hand one of the short type bars 20 is provided with a double type block and several of those short type bars near the middle of 60 the system where the flare is less pronounced are also so provided. In the present instance the six type bars 20 nearest the middle of the system are shown provided with double type blocks, and the remaining shorter type 65 bars, except the left-hand end one, are shown

provided with single type blocks; but this number can be varied, and it can be increased by providing suitable bends in some of the long type bars 21.

The number of type bars and keys can also be varied. In the present instance I have shown thirty-six short type bars and thirty-six long type bars making seventy-two in all; and I have shown seventy-two keys arranged in six rows of twelve each. The keys of the three rear rows are connected with the short type bars 20 as indicated in the diagram, Fig. 6, and the keys of the three front rows are connected with the long type bars 21. It will of course be understood that those type bars carrying single types can be used only when the platen is in lower case position and the remaining type bars can be used when the platen is in either the upper case or lower case position, printing upper case characters in one instance and lower case characters in the other. In the arrangement described there are forty-three type bars provided with two types each, and, therefore, printing eighty-six characters; and there are twenty-nine type bars carrying single types and therefore adapted to print twenty-nine characters. The whole machine therefore has one hundred and fifteen characters. For the convenience of the operator and in order to prevent mistakes in using the machine I have marked the printing keys 13 in two distinctive ways. As shown in the drawings, those keys that are connected with double types are shown with white tops and black characters, while those connected with single types are shown with dark tops and white characters. In the diagram Fig. 6 the connections from the keys to the type bars are indicated diagrammatically by broken lines 16, these representing roughly the links 16 and the other devices connecting the several keys with their respective type bars. It will be understood that in the machine the lower arms of the several bell cranks 15 are bent toward the right or toward the left in order to prevent interference between the various links 16 and this fact is indicated in a way in the diagram.

In the present instance I have used the Roman characters for writing German and in adapting the machine for that language and the Russian, I have availed myself of any instances in which the characters used in the two languages are either identical or else resemble each other so closely as that a single type can serve for both. In the Russian language in most instances the difference between upper case and lower case characters is only a difference in size with little or no difference in shape, and in some instances where these characters resemble the capital letters of the Roman alphabet I have used one of the double types to print 120

the letter both large and small for the Russian and have provided one of the single types with the corresponding Roman small letter. This is true of the B, of the M and some others; but the Roman small b, m, etc., do not occur in the Russian and accordingly one of the single types is provided to print each of those characters. One of the Russian letters so nearly resembles the Arabic numeral 3 as that a single type can be used for both. I have also used some of the single type to print certain vowels with the German *umlaut*, thus avoiding the necessity which would otherwise exist of providing any so-called "accent mechanism"; that is to say, by this means it is rendered unnecessary to arrange some of the keys so that they operate the ribbon vibrator without operating the carriage escapement.

Some of the double type bars and keys have also been utilized to write the Roman capital and small letters where neither of these resembles any Russian character. This is true of the J key and type bar for example, and on the other hand in some instances two such characters are printed by two of the single type bars, the letters W and F being instances.

In some cases of which the letters X, A and I are examples, the Russian and Roman letters, both capital and small, are either identical or else are so nearly alike that one double type answers for each of these letters in both languages.

Various changes can be made in the details of construction and arrangement without departing from my invention.

What I claim as new and desire to secure by Letters Patent, is:—

1. The combination with a shiftable platen frame having a rail, of a rock shaft, an arm projecting from said shaft toward the front of the machine and having a shift key, an arm projecting from the middle of said shaft toward the rear of the machine, a post pivoted to said rear arm, a roller or wheel for said rail carried by said post, and a guide link for the upper end of said post.

2. The combination with a shiftable platen and platen frame, of means for shift-

ing said frame said means consisting of a lever of the first order in the base of the machine, said lever having two forward arms carrying shift keys and one rearward arm at the middle of the machine, a post carried by said rearward arm, means at the upper end of said post to shift the platen frame, and a guide for the upper end of said post.

3. In a typewriting machine, the combination with a platen, a carriage truck, and a platen frame shiftably mounted in said truck and comprising a rail, of a post having a wheel for coöperation with said rail, a lever arm for moving said post up and down and for supporting and guiding the lower end of said post, and guiding means for the upper part of said post, said upper guiding means consisting of a link having two parallel bars and a connecting bar, one of said parallel bars being pivoted to the frame of the machine and the other to said post.

4. In a typewriting machine, the combination with a platen and a shiftable platen frame having a rail, of means for shifting said frame comprising post 63 having wheel 60 and bracket 82, said wheel coöperating with said rail, and the guide link comprising arm 76, wide bearing part 78 pivoted to said bracket 82, and also wide bearing part 77 86 pivoted to the frame of the machine.

5. The combination with a shiftable platen and platen frame comprising a bar which constitutes a rail, of means for shifting said platen and frame comprising a vertical post having thereon a wheel on which said rail travels and having a bracket with ears spaced apart, a guide link pivoted in said spaced ears and pivoted also to the fixed framework, and means for shifting said post.

Signed at the borough of Manhattan, city of New York, in the county of New York and State of New York, this 25th day of Jan. A. D. 1916.

JOHN H. BARR.
